(57) **ABSTRACT**

A vehicle mounted garbage bin cleaning system includes a pair of arms configured for lifting a garbage bin, the arms rotatably coupled to a mount on a vehicle, a hopper configured for accepting the garbage bin when the arms lift the garbage bin into the hopper, spray rods extending upwards from the hopper and that spray water jets to clean an interior of the garbage bin, a gas-powered motor that uses a mechanical means to drive two pressure washer pumps, and wherein the spray rods are fluidically coupled with the two pressure washer pumps.

GARBAGE BIN CLEANING SYSTEM WITH GAS MOTOR

CROSS-REFERENCE TO RELATED APPLICATIONS

This patent application is a continuation in part of, and claims priority to, patent application Ser. No. 18/518,009 filed Nov. 22, 2023 and titled "Side-Mounted Garbage Bin Cleaning System. The subject matter of patent application Ser. No. 18/518,009 is hereby incorporated by reference in its entirety.

STATEMENT REGARDING FEDERALLY SPONSORED RESEARCH OR DEVELOPMENT

Not Applicable.

INCORPORATION BY REFERENCE OF MATERIAL SUBMITTED ON A COMPACT DISC

Not Applicable.

TECHNICAL FIELD

The technical field relates generally to garbage bin cleaning systems and, more specifically, to vehicle mounted garbage bin cleaning systems for thoroughly cleaning and deodorizing garbage bins in a highly automated manner.

BACKGROUND

Sanitation is a critical feature in any society, as it is a requirement for providing desirable living conditions. Sanitation being improperly performed can and does lead to sickness and even death on a massive scale. To this end, the disposal of garbage from commercial establishments, residential homes and apartment houses is generally handled by garbage trucks equipped to handle garbage bins. These trucks have the capability of lifting the bins and dumping the contents thereof into a compactor from where the compacted trash is pushed by a ram into the back of the truck for dumping. Particularly in the case of restaurants and apartment houses where the trash contains a considerable amount of organic material, the garbage bins may become unpleasantly odorous, even after having been emptied, and can present a health problem.

The current solutions for washing and disinfecting garbage bins are largely unacceptable. Manually washing and disinfecting garbage bins can be time consuming and tedious for a person to perform, as well as labor intensive. Automated processes may be employed, such as through the use of tank trucks equipped with a hoisting device and a separate pump unit adapted to provide water jets for sprinkling the interior walls of the garbage bin, with the bin being suspended from the hoisting device. The automated processes, however, are usually limited in scope and extent, requiring multiple passes for a complete cleaning. Conventional automated processes for washing and disinfecting garbage bins can also leave many interior areas of a garbage bin untouched, with a large proportion of the dirt stubbornly adhering on the garbage bin walls. The known automated processes may also use exorbitant amounts of water per garbage bin, thereby resulting in large amounts of water waste. Conventional automated processes for washing and

disinfecting garbage bins may further cause runoff of the wastewater into the environment, which can be damaging.

One of the significant challenges in implementing a mobile bin cleaning system is the difficulty of powering multiple pressure washer pumps on a vehicle. Pressure washer pumps require a substantial amount of power to operate effectively, especially when tasked with thoroughly cleaning and disinfecting garbage or recycling bins, which often contain stubborn dirt and grime. In a mobile setup, the power source is typically the vehicle's engine, which is already burdened with the primary task of transportation. Adding multiple high-powered pressure washer pumps puts an additional load on the engine, leading to increased fuel consumption and potential wear and tear. Moreover, the need for a consistent and robust power supply to operate these pumps at optimal performance further complicates the design. The integration of such equipment into a standard vehicle poses significant engineering challenges, not only in terms of power management but also considering the space and weight constraints of the vehicle.

Furthermore, the deployment of multiple pressure washer pumps in a mobile setting raises concerns regarding energy efficiency and environmental impact. While these pumps are necessary for effective cleaning, their energy demands can be substantial, leading to higher emissions from the vehicle. This is particularly problematic in urban settings where pollution control is crucial. The challenge, therefore, lies in balancing the need for effective cleaning power with the imperative of minimizing environmental impact. This balance requires innovative solutions, in order to make the mobile bin cleaning process both effective and sustainable.

Therefore, a need exists for improvements over the prior art, and more particularly for improved systems and apparatuses for quickly and efficiently performing a proper cleaning and disinfecting regimen for garbage bins.

SUMMARY

A vehicle mounted garbage bin cleaning system is provided. This Summary is provided to introduce a selection of disclosed concepts in a simplified form that are further described below in the Detailed Description including the drawings provided. This Summary is not intended to identify key features or essential features of the claimed subject matter. Nor is this Summary intended to be used to limit the claimed subject matter's scope.

In one embodiment, the vehicle mounted garbage bin cleaning system includes a pair of arms configured for lifting a garbage bin, the pair of arms rotatably coupled to a mount on a vehicle, a hopper configured for accepting the garbage bin when the pair of arms lifts the garbage bin into the hopper, at least two spray rods extending upwards from the hopper and configured to wash an interior of the garbage bin, each of the at least two spray rods including at least one high-pressure, rotating water nozzle that sprays a water jet, wherein when the pair of arms lifts the garbage bin into the hopper, the at least two spray rods are situated within the garbage bin, and a gas powered motor coupled to the vehicle, a mechanical means coupled with the gas powered motor such that the gas powered motor drives the mechanical means, a first pressure washer pump mechanically coupled to the mechanical means such that the mechanical means drives the first pressure washer pump, a second pressure washer pump mechanically coupled to the mechanical means such that the mechanical means drives the second pressure washer pump, the at least two spray rods are both fluidically coupled with the first and second pres-

sure washer pumps, respectively, such that the first and second pressure washer pumps provide pressurized water to at least two spray rods, respectively.

BRIEF DESCRIPTION OF THE DRAWINGS

The accompanying drawings, which are incorporated in and constitute a part of this disclosure, illustrate various example embodiments. In the drawings:

FIG. 1A is a drawing depicting a block diagram of the pressure washing system of the vehicle-mounted garbage bin cleaning system, according to an example embodiment.

FIG. 1B is a drawing depicting a more detailed block diagram of the mechanical means of the pressure washing system of the vehicle-mounted garbage bin cleaning system, according to an example embodiment.

FIG. 1C is a drawing depicting a gas-powered motor and pressure washer pumps of the pressure washing system of the vehicle-mounted garbage bin cleaning system, according to an example embodiment.

FIG. 2 is a drawing depicting a side view of the vehicle-mounted garbage bin cleaning system, showing the pairs of arms in the down position, according to an example embodiment.

FIG. 3 is a drawing depicting a rear view of the vehicle-mounted garbage bin of FIG. 2, showing the pairs of arms in the down position, according to an example embodiment.

FIG. 4 is a drawing depicting a top perspective view of the pairs of arms in the down position, according to an example embodiment.

FIG. 5 is a drawing depicting a side view of the vehicle-mounted garbage bin of FIG. 2, showing the pairs of arms in the up position, according to an example embodiment.

FIG. 6 is a drawing depicting a rear view of the vehicle-mounted garbage bin of FIG. 2, showing the pairs of arms in the up position, according to an example embodiment.

FIG. 7 is a drawing depicting a top perspective view of the vehicle-mounted garbage bin of FIG. 2, showing the pairs of arms in the up position, according to an example embodiment.

FIG. 8 is a drawing depicting a top perspective view of the vehicle-mounted garbage bin of FIG. 2, showing the pairs of arms in the down position while holding a bin, according to an example embodiment.

FIG. 9 is a drawing depicting a top perspective view of the vehicle-mounted garbage bin of FIG. 2, showing the pairs of arms in the up position while holding the bin, according to an example embodiment.

FIG. 10 is a drawing depicting a side view of the vehicle-mounted garbage bin of FIG. 2, showing the pair of arms in the down position, according to an example embodiment.

FIG. 11A is a diagram depicting the interface of the control panel of the vehicle-mounted garbage bin cleaning system, according to an example embodiment.

FIG. 11B is a diagram depicting an alternative interface of the control panel of the vehicle-mounted garbage bin cleaning system, according to an example embodiment.

FIG. 12 is a block diagram depicting the control structure of the washing system and the lifting system of the vehicle-mounted garbage bin cleaning system, according to an example embodiment.

FIG. 13 is a block diagram of a system including an example computing device and other computing devices

numbers are used in the drawings and the following description to refer to the same or similar elements. While embodiments may be described, modifications, adaptations, and other implementations are possible. For example, substitutions, additions, or modifications may be made to the elements illustrated in the drawings, and the methods described herein may be modified by substituting, reordering, or adding stages to the disclosed methods. Accordingly, the following detailed description does not limit the claimed subject matter. Instead, the proper scope of the claimed subject matter is defined by the appended claims.

The claimed subject matter improves over the prior art by providing a simple, cost-effective, and efficient vehicle-mounted garbage bin cleaning system configured for cleaning both large and small garbage bins, such as waste, compost and recycling bins. The claimed subject matter improves sanitation by allowing for larger number of large and small garbage bins to be cleaned at the curbside in smaller amounts of time, using a minimum of labor or manual user involvement. The claimed subject matter is particularly useful in the case of restaurants and apartment houses where the trash contains a considerable amount of organic material.

The improvement in the prior art is significantly attributed to the integration of a gas-powered engine that directly powers two pressure washer pumps, a design choice that brings multiple benefits to the vehicle-mounted garbage bin cleaning system. This direct powering method enhances the efficiency of the system by providing a dedicated and robust energy source, specifically tailored for the high demands of pressure washing. Unlike systems that rely on the vehicle's primary engine, this approach minimizes the strain on the vehicle's overall power system, leading to better fuel efficiency and reduced wear and tear. Furthermore, by having a dedicated gas-powered engine for the pressure washers, the system ensures consistent performance, regardless of the vehicle's operational state, whether idling or in transit. This specialization not only enhances the cleaning capabilities, especially for stubborn organic waste commonly found in restaurant and apartment house bins, but also streamlines the cleaning process, allowing for a larger number of bins to be cleaned in a shorter time frame. The direct power approach, thus, significantly improves the operational efficiency and effectiveness of the cleaning system, making it a substantial advancement over previous methods.

The claimed subject matter also improves over the prior art by using a simple automated process that allows for garbage bins to be cleaned thoroughly by the claimed system. The claimed subject matter also thoroughly washes and disinfects garbage bins without using exorbitant amounts of water per garbage bin, thereby resulting in a reduction of water waste. The claimed subject matter also does not cause runoff of the wastewater into the environment, which is environmentally friendly. Furthermore, the claimed subject matter also efficiently cleans garbage bins at the curb and returns it to the curb, thereby increasing throughput and reducing physical labor.

Additionally, the claimed subject matter utilizes a computerized system that automates the process of lifting the garbage bins into place within the hopper, activating the washing system, and resting the garbage bins into place on the ground, while reducing intervention and input by a human driver or operator. This leads to a time saving and a reduction in operator errors. The claimed subject matter also improves over the prior art by using an automated process that allows for garbage bins to be cleaned in a cautious manner that increases safety for operators and users.

DETAILED DESCRIPTION

The following detailed description refers to the accompanying drawings. Wherever possible, the same reference

FIG. 1A is a drawing depicting a block diagram of the gas-motor driven pressure washing system 100 of the vehicle-mounted garbage bin cleaning system, according to an example embodiment. FIG. 1A shows that the gas-motor driven pressure washing system 100 of the vehicle-mounted garbage bin cleaning system comprises a gas-motor 125, which may be an internal combustion engine in which the combustion of a fuel occurs with an oxidizer (usually air) in a combustion chamber. In an internal combustion engine, the expansion of the high-temperature and high-pressure gases produced by combustion applies direct force to some component of the engine. The force is applied to pistons that move the component over a distance, transforming chemical energy into kinetic energy which is used to propel, move or power a shaft or pulley attached to the engine.

FIG. 1A further shows that the gas-motor driven pressure washing system 100 includes at least a first mechanical means 135 coupling the motor 125 (described in greater detail below) to the pressure washer pumps 128, 138. The mechanical means used include mechanical devices to convey mechanical energy from the gearbox to another location or element, namely, the pressure washer pumps. The mechanical means is described in greater detail below. In one embodiment, the mechanical means 135 is integrated into one combined system.

FIG. 1A further shows that the gas-motor driven pressure washing system 100 includes at least a first pressure washer pump 128 mechanically coupled to the first mechanical means 135, and a second pressure washer pump 138 mechanically coupled to the mechanical means 135. One, two or more spray rods 129 are fluidically coupled to the pressure washer pump 128, and one, two or more spray rods 139 are fluidically coupled to the pressure washer pump 138. A pressure washer pump is a water pump configured to pump water at high pressures suitable for pressure washing. A water pump is a device that moves water by mechanical action. The water pump may be a direct lift, positive displacement, impulse, velocity, gravity, steam or valveless water pump. The water pump transports water from the reservoir or water tank 130 at high pressure to the spray heads. In one embodiment, a spray rod is a tubular element that acts as a conduit for the transfer of fluid, such as water or washing fluid. In another embodiment, a spray rod is any conduit for the transfer of fluid, such as rotating rod that sprays water from both ends, and a base to which said rotating rod is attached.

FIG. 1A shows that the gas-motor driven pressure washing system 100 can be used to power more than one pressure washing pumps 128, 138 to expel high pressure water jets from more than one set of spray rods 129, 139, wherein each set of spray rods includes one, two or more spray rods. As a result, the pressure washing system 100 can be used to pressure clean garbage, waste, compost and recycle bins, using the multiple sets of spray rods 129, 139 at the same time. This feature increases the throughput of the system 100, in addition to increasing the volume of garbage bins that can be washed in a given period of time.

Note that although FIG. 1A shows the pressure water pumps 128, 138 being powered by mechanical means which is powered by a motor 125, in another embodiment, the pressure water pumps 128, 138 may be powered by a hydraulic system wherein the motor powers a hydraulic pump, which, in turn, powers the pressure washer pumps.

FIG. 1B is a block diagram depicting a more detailed view of the mechanical means 135 of the gas-motor driven pressure washing system 100 of the vehicle-mounted garbage bin cleaning system, according to an example embodiment.

ment. FIG. 1B depicts the flow of power from the motor 125 to the pressure washer pumps 128, 138 via the mechanical means 135. The diagram shows a motor 125 mechanically coupled with the pressure washer pumps 128, 138 via the mechanical means 135.

FIG. 1B further shows a driveshaft 181 that is rotated by the motor. The driveshaft 181 is coupled to a first pulley 182 such that when the driveshaft 181 rotates, the first pulley 182 is rotated. A pulley is a wheel on an axle or shaft that is designed to support movement or transfer of power between the axle or shaft and a cable or belt. The driveshaft 181 may be coupled to the center point or the axle of first pulley 182 such that the longitudinal axis of the driveshaft is colinear with the center point or axle of the circular pulley. The first pulley 182 is coupled to a pulley 183 via a belt 184 such that when the first pulley rotates, the pulley 183 is rotated. A belt is a loop of flexible material used to link two or more rotating pulleys or shafts mechanically. The pulley 183 is coupled to a shaft 185 such that when the pulley 183 rotates, the shaft 185 is rotated. The shaft 185 may be coupled to the center point or the axle of pulley 183 such that the longitudinal axis of the shaft is colinear with the center point or axle of the circular pulley. The shaft 185 is coupled to the pressure washer pump 128 such that when the shaft 185 rotates, the pressure washer pump 128 is powered via the rotational kinetic energy of the shaft 185. Similar to items 181-185, on the right side of the motor 125 is a driveshaft 191 attached to a pulley 192, which drives another pulley 193 via a belt 194, wherein pulley 193 is attached to shaft 195, which powers pressure washer pump 138. In one embodiment, the mechanical means 135 of the gas-motor driven pressure washing system 100 of the vehicle-mounted garbage bin cleaning system includes elements 181-185, 191-195.

FIG. 1C is a drawing depicting a gas-powered motor 125 and pressure washer pumps 128, 138 of the pressure washing system 100 of the vehicle-mounted garbage bin cleaning system, according to an example embodiment.

FIG. 2 is a drawing depicting a side view of another embodiment of the vehicle-mounted garbage bin cleaning system 200, showing two pairs of arms 231, 232 in the down position, according to an example embodiment. FIG. 3 depicts a rear view of the vehicle-mounted garbage bin cleaning system of FIG. 2, and FIG. 4 depicts a top perspective view of the vehicle-mounted garbage bin cleaning system of FIG. 2. The vehicle-mounted garbage bin cleaning system includes a mount 206, to which each of the two pairs of arms 231, 232 are independently attached. The vehicle-mounted garbage bin cleaning system also includes a hopper 204. The two pairs of arms comprise the first pair of arms 231 and a second pair of arms 232. Each pair of arms may move simultaneously coordinated (i.e., move from one position to another position). Alternatively, the first pair of arms 231 and the second pair of arms 232 may move independently from one another, such that one pair of arms may be activated (i.e., move from one position to another position) without activating the other pair. FIGS. 2-4 further show the spray heads 312, 314 located within the hopper 204.

The vehicle-mounted garbage bin cleaning system 200 may be coupled to the trailer element 202 of a vehicle, such as an industrial truck. The vehicle-mounted garbage bin cleaning system includes two pairs of arms 231, 232 configured for lifting garbage bins, such as a trash can, recycling container, dumpster, rubbish bin, etc. Said dumpster may measure approximately 2, 4, 6, 8 or 10 cubic yards in volume, 70-85 inches wide, 45-95 inches high and 39-75

inches deep. Said bin may be a 35-95-gallon recycling bin and may measure approximately 35-95 gallons in volume, 20-29 inches wide, 38-45 inches high and 23-34 inches deep.

The two pairs of arms 231, 232 may be coupled to piston-activated levers that are themselves rotatably coupled to an L-shaped member 210 which is itself rotatably coupled to a mount 206 on the vehicle via a pivot point 208. The mount 206 may comprise one or more triangular elements located on either side of the trailer bed 202. The topmost vertex of the triangular elements comprise the pivot point 208. The mount 206 may also comprise further structure between the two triangular elements, to which the L-shaped element is attached.

The L-shaped element is moved up and down into the up position and down position via a hydraulic element at the pivot point 208. The hydraulic element at the pivot point 208 moves the L-shaped element to pivot or rotate around the pivot point. This action rotates the L-shaped element substantially 90 to 180 degrees into the up position, so as to turn the garbage bins 802, 804 substantially upside down or nearly upside down. The opposite action rotates the L-shaped element substantially 90 to 180 degrees into the down position, so as to turn the garbage bins 802, 804 substantially right side up.

The vehicle-mounted garbage bin cleaning system 200 further comprises a hopper 204 configured for accepting garbage bins when the pairs of arms lift the garbage bins into the hopper. The vehicle-mounted garbage bin cleaning system further comprises two pairs of arms 231, 232, each pair of arms is configured to allow for garbage bins to be raised and lifted into the hopper for pressure cleaning at the same time.

FIG. 3 also shows at least two spray rods 302, 304 extending upwards from the hopper 204, each spray rod including at least one high-pressure, rotating water nozzle 312, 314 that sprays a water jet. In another embodiment, each spray rod includes a plurality of high-pressure, rotating water nozzles that spray water jets.

The hopper is configured to catch substantially all water that is sprayed into the garbage bins by the at least two spray rods. FIG. 9 also shows that when the pairs of arms 231, 232 lift the garbage bins into the hopper, one or more of the at least two spray rods may be situated within the garbage bins (or near the opening of the garbage bins) so as to wash and clean the interior thereof with the corresponding rotating water nozzles 312, 314 that spray water jets.

FIG. 4 provides a closer look at the first pair of arms 231 and a second pair of arms 232. Each pair of arms may move simultaneously coordinated (i.e., move from one position to another position). Alternatively, the first pair of arms 231 and the second pair of arms 232 may move independently from one another, such that one pair of arms may be activated (i.e., move from one position to another position) without activating the other pair. The first pair of arms 231 comprises arms 212, 402 while the second pair of arms 232 comprises arms 404, 406.

FIG. 5 is a drawing depicting a side view of the vehicle-mounted garbage bin cleaning system 200 of FIG. 2, showing two pairs of arms 231, 232 in the up position, according to an example embodiment. FIG. 6 depicts a rear view of the vehicle-mounted garbage bin cleaning system 200 of FIG. 5, and FIG. 7 depicts a top perspective view of the vehicle-mounted garbage bin cleaning system 200 of FIG. 5. FIGS. 5-7 show that the vehicle-mounted garbage bin cleaning system 200 is configured such that the two pairs of arms 231, 232 can be lifted into the up position such that bins may be

moved into the hopper for cleaning. Though the first pair of arms 231 and the second pair of arms 232 are shown both moving to the up position simultaneously at the same time, they are also configured to move independently from one another, such that one pair of arms may be activated without activating the other pair. FIGS. 6-7 further show that when the first pair of arms 231 and the second pair of arms 232 are moved to the up position, the spray heads 312, 314 are located centrally within the space between each pair of arms. 10 That is, each spray head is located in between a pair of arms, thereby being ideally located for optimal cleaning of the bins by the spray heads.

FIG. 8 is a drawing depicting a top perspective view of the vehicle-mounted garbage bin cleaning system 200 of FIG. 2, 15 showing the two pairs of arms 231, 232 in the down position, wherein each pair of arms is grabbing a bin, according to an example embodiment. FIG. 8 shows that the first pair of arms 231 has grabbed the bin 802 and the second pair of arms 232 has grabbed the bin 804, while both pairs of arms 20 are in the down position. The first pair of arms 231 may grab the bin 802 and the second pair of arms 232 may grab the bin 804 simultaneously, or each bin may be grabbed at a different time. Next, the first pair of arms 231 and the second pair of arms 232 will be moved to the up position to clean 25 the bins 802, 804.

FIG. 9 is a drawing depicting a top perspective view of the vehicle-mounted garbage bin cleaning system 200 of FIG. 2, 30 showing two pairs of arms 231, 232 in the up position and lifting bins 802, 804 into the hopper 204, according to an example embodiment. FIG. 9 shows that the first pair of arms 231 has grabbed the bin 802 and the second pair of arms 232 has grabbed the bin 804, and both pairs of arms 35 have been moved to the up position, thereby moving the bins 802, 804 into the hopper for the purpose of cleaning the bins using the spray heads 312, 314 located within the hopper 204. Note that in the up position, each of the spray heads 312, 314 is located centrally within one of the bins 802, 804, thereby being ideally located for optimal cleaning of the bins. The bins 802, 804 may be moved to the up position by 40 the two pairs of arms 231, 232 simultaneously, or each bin may be moved to the up position at different times, since the two pairs of arms 231, 232 may move independently of each other.

FIG. 10 is a drawing depicting a side view of the 45 vehicle-mounted garbage bin cleaning system 200 of FIG. 2, including an attached vehicle 1000, showing two pairs of arms 231, 232 in the down position, according to an example embodiment. The vehicle-mounted garbage bin cleaning system 200 may be coupled to the trailer 202 of the vehicle 50 1000, such as an industrial truck.

In another embodiment, the vehicle-mounted garbage bin 55 cleaning system 200 may further include a control panel for controlling the two pairs of arms 231, 232, the water jets sprayed by the at least two spray rods 302, 304. The control panel may be a flat and/or vertical area where control 60 (buttons, sliders, dials, etc.) or monitoring instruments (monitor, display, digital readout, etc.) are displayed and located in an area that users can access. The control panel may be equipped with push buttons and analog instruments, or, alternatively, touchscreens, used for monitoring and control purposes. A user can utilize the control panel to control the up and down positions of the two pairs of arms 231, 232, whether and when the water jets are sprayed by the 65 at least two spray rods, when the bins are in the optimal location within the hopper, for optimal cleaning effect. In one embodiment, the control panel is connected to one or more of the PLCs 1250, 1270 and 1290 and the control panel

is configured to interface with any such one or more PLCs to automatically activate the first and second pair of arms to simultaneously lift the first and second garbage bins into the hopper, automatically activate the pressure washing system to spray water jets, etc.

FIG. 11A is a diagram depicting the interface of the control panel 1110 for controlling the pairs of arms 231, 232 and the water jets sprayed by the spray rods. The control panel may be a flat and/or vertical area where control buttons 1112-1116 are displayed and located in an area that users can access. The control panel may be equipped with push buttons to control the up and down positions of the pairs of arms, whether and when the water jets are sprayed by the spray rods, when the bins are in the optimal location within the hopper. In one example, when the truck is in place adjacent to one or more garbage bins such that the pairs of arms in the down position are positioned next to the bin, the user may activate the lifting system 1260 by pushing the button 1112 which activates the arms to grab the bin. Next, the user may push the button 1113 to activate the lifting system 1260 to lift the bin into the hopper 204. Then, the user may push the button 1114 to activate the washing system 1240 to spray and wash the bin in the hopper 204. Then, the user may push the button 1115 to activate the lifting system 1260 to lower the bin from the hopper 204 and onto the ground, and push button 1116 to let the bin go from the pair of arms. In one alternative embodiment, the push of only one button may result in the sequence above being activated all at once in the sequence listed above.

Similar to FIG. 11A, FIG. 11B is a diagram depicting an alternative interface of a control panel 1150 for controlling the pairs of arms, and the water jets sprayed by the spray rods. The control panel 1150 may be a flat and/or vertical area where a plurality of control buttons 1154 are displayed and located in an area that users can access. Said buttons 1154 may be similar to the buttons described with reference to FIG. 11A, including the functionality thereof. The control panel 1150 may also include a joystick 1152 wherein the user or operator of the truck utilizes the joystick to control the pairs of arms and member 210 to maneuver the arms so as to situate the arms in the correct location, so as to be able to grab the garbage bin 802, as shown in FIG. 8. Also, in one embodiment, the pairs of arms may include a sliding mechanism such that the arms slide on a supporting structure such that, when activated using the control panel, the arms can move back and forth on the supporting structure. Said sliding mechanism may be controlled by the joystick 1152. This feature allows the truck to be situated farther away from the garbage bin sitting on the ground, while still allowing the arms to grab the garbage bin, since the arms may move forward.

FIG. 12 is a block diagram depicting the control structure of the washing system 1240, the lifting system 1260 of the vehicle-mounted garbage bin cleaning system, according to an example embodiment. The lifting system 1260 may refer to the items discussed in FIGS. 2-10 and any other items that are required for the proper functioning of the pair of arms, such as the associated electrical system. The washing system 1240 may refer to the items shown in FIG. 1B and any other items that are required for the proper functioning of the washing system.

Similarly, washing system 1240, which comprises the system 100 of FIG. 1B, acts to sanitize garbage bins by washing them, and the lifting system 1260 acts to lift the garbage bins into the hopper 1402 so that the washing system 1240, may perform its functions.

In one embodiment, the lifting system 1260 is controlled by a programmable logic controller 1270, and the washing system 1240 is controlled by a programmable logic controller 1250. Programmable logic controllers (PLCs) are industrial computers that have been ruggedized and specifically designed or adapted for the control of machines and processes by providing instructions to the aforementioned machines. The programmable logic controllers may come in the form of single board computers, application-specific integrated circuits, or printed circuit board assemblies. In another embodiment, the programmable logic controllers 1270, 1250 are all controlled by a master programmable logic controller 1290. In yet another embodiment, the lifting system 1260, the washing system 1240 are all directly controlled by the master programmable logic controller 1290.

The claimed subject matter utilizes said computerized system of FIG. 12 to automate the process of activating the lifting system 1260 to lift the garbage bins into place within the hopper, activating and deactivating the washing system 1240, and activating the lifting system 1260 to lower the garbage bins into place on the ground, without requiring intervention and input by a human driver or operator. This leads to a time saving and a reduction in operator errors. One or more of the programmable logic controllers 1250, 1270, 1290 may be programmed with timing sequences embodied in a programming module stored on the PLC (see programming module below). For example, a PLC may be programmed to, in response to receiving an activation signal from a user interface, activate the lifting system 1260 for a set period of time to lift the garbage bins into place within the hopper, and then deactivate the lifting system 1260 while holding the garbage bins in place. The lifting system may be activated by providing power to the piston-activated levers that are rotatably coupled to the pairs of arms, which is itself rotatably coupled to a mount 206 on the vehicle via a pivot point 208, thereby lifting the pairs of arms. The lifting system may be deactivated by ceasing providing the power provided above.

Then, a PLC may be programmed to automatically activate the washing system 1240 for a set period of time to clean the garbage bins while in the hopper, and then deactivate the washing system 1240. The washing system may be activated by engaging the pressure washer pump(s) 128, 138 via the power provided by the motor 125, thereby spraying water out of the spray rods 129, 139. Said activation may occur immediately after the deactivation of the lifting system above. The washing system may be automatically deactivated by disengaging the pressure washer pump(s) 128, 138 from the power provided by the motor 125.

Then, a PLC may be programmed to activate lifting system 1260 to lower the garbage bins into place on the ground. Said activation may occur immediately after the deactivation of the deodorizing system above. A PLC may be programmed to automatically activate the lifting system 1260 for a set period of time to lower the garbage bins onto the ground, and then deactivate the lifting system 1260. The lifting system may be activated by providing power to the piston-activated levers that are rotatably coupled to the pairs of arms, which is itself rotatably coupled to a mount 206 on the vehicle via a pivot point 208, thereby lowering the pair of arms. The lifting system may be deactivated by ceasing providing the power provided above. In one embodiment, the control panel is connected to one or more of the PLCs 1250, 1270 and 1290 and the control panel is configured to interface with any such one or more PLCs to automatically activate the first and second pair of arms to simultaneously

11

lift the first and second garbage bins into the hopper, and automatically activate the pressure washing system to spray water jets.

FIG. 13 is a block diagram of a system including an example computing device 1300 and other computing devices. Consistent with the embodiments described herein, the aforementioned actions performed by any PLC or combination thereof may be implemented in a computing device, such as the computing device 1300 of FIG. 13. Any suitable combination of hardware, software, or firmware may be used to implement the computing device 1300. The aforementioned system, device, and processors are examples and other systems, devices, and processors may comprise the aforementioned computing device. Furthermore, computing device 1300 may comprise an operating environment for systems 100 and 1200, as described above. The processes described in this description may operate in other environments and are not limited to computing device 1300.

With reference to FIG. 13, a system consistent with an embodiment may include a plurality of computing devices, such as computing device 1300. In a basic configuration, computing device 1300 may include at least one processing unit 1302 and a system memory 1304. Depending on the configuration and type of computing device, system memory 1304 may comprise, but is not limited to, volatile (e.g., random-access memory or RAM), nonvolatile (e.g., read-only memory or ROM), flash memory, or any combination or memory. System memory 1304 may include operating system 1305, and one or more programming modules 1306. Operating system 1305, for example, may be suitable for controlling computing device 1300's operation. In one embodiment, programming modules 1306 may include, for example, a program module 1307 for executing the actions of the PLC's described above, or any combination thereof. Furthermore, embodiments may be practiced in conjunction with a graphics library, other operating systems, or any other application program and is not limited to any particular application or system. This basic configuration is illustrated in FIG. 13 by those components within a dashed line 1320.

Computing device 1300 may have additional features or functionality. For example, computing device 1300 may also include additional data storage devices (removable and/or non-removable) such as, for example, magnetic disks, optical disks, or tape. Such additional storage is illustrated in FIG. 13 by a removable storage 1309 and a non-removable storage 1310. Computer storage media may include volatile and nonvolatile, removable and non-removable media implemented in any method or technology for storage of information, such as computer readable instructions, data structures, program modules, or other data. System memory 1304, removable storage 1309, and non-removable storage 1310 are all computer storage media examples (i.e., memory storage.) Computer storage media may include, but is not limited to, RAM, ROM, electrically erasable read-only memory (EEPROM), flash memory or other memory technology, CD-ROM, digital versatile disks (DVD) or other optical storage, magnetic cassettes, magnetic tape, magnetic disk storage or other magnetic storage devices, or any other medium which can be used to store information and which can be accessed by computing device 1300. Any such computer storage media may be part of device 1300. Computing device 1300 may also have input device(s) 1312 such as a keyboard, a mouse, a pen, a sound input device, a camera, a touch input device, etc. Output device(s) 1314 such as a display, speakers, a printer, etc. may also be included. Computing device 1300 may also include a vibration device capable of initiating a vibration in the device on

12

command, such as a mechanical vibrator or a vibrating alert motor. The aforementioned devices are only examples, and other devices may be added or substituted.

Computing device 1300 may also contain a network connection device 1315 that may allow device 1300 to communicate with other computing devices 1318, such as over a network in a distributed computing environment, for example, an intranet or the Internet. Device 1315 may be a wired or wireless network interface controller, a network interface card, a network interface device, a network adapter or a LAN adapter. Device 1315 allows for a communication connection 1316 for communicating with other computing devices 1318. Communication connection 1316 is one example of communication media. Communication media may typically be embodied by computer readable instructions, data structures, program modules, or other data in a modulated data signal, such as a carrier wave or other transport mechanism, and includes any information delivery media. The term "modulated data signal" may describe a signal that has one or more characteristics set or changed in such a manner as to encode information in the signal. By way of example, and not limitation, communication media may include wired media such as a wired network or direct-wired connection, and wireless media such as acoustic, radio frequency (RF), infrared, and other wireless media. The term computer readable media as used herein may include both computer storage media and communication media.

As stated above, a number of program modules and data files may be stored in system memory 1305, including operating system 1305. While executing on processing unit 1302, programming modules 1306 (e.g. program module 1307) may perform processes including, for example, one or more of the stages of the process 300 as described above. The aforementioned processes are examples, and processing unit 1302 may perform other processes. Other programming modules that may be used in accordance with embodiments herein may include electronic mail and contacts applications, word processing applications, spreadsheet applications, database applications, slide presentation applications, drawing or computer-aided application programs, etc.

Generally, consistent with embodiments herein, program modules may include routines, programs, components, data structures, and other types of structures that may perform particular tasks or that may implement particular abstract data types. Moreover, embodiments herein may be practiced with other computer system configurations, including handheld devices, multiprocessor systems, microprocessor-based or programmable consumer electronics, minicomputers, mainframe computers, and the like. Embodiments herein may also be practiced in distributed computing environments where tasks are performed by remote processing devices that are linked through a communications network. In a distributed computing environment, program modules may be located in both local and remote memory storage devices.

Furthermore, embodiments herein may be practiced in an electrical circuit comprising discrete electronic elements, packaged or integrated electronic chips containing logic gates, a circuit utilizing a microprocessor, or on a single chip (such as a System on Chip) containing electronic elements or microprocessors. Embodiments herein may also be practiced using other technologies capable of performing logical operations such as, for example, AND, OR, and NOT, including but not limited to mechanical, optical, fluidic, and

13

quantum technologies. In addition, embodiments herein may be practiced within a general-purpose computer or in any other circuits or systems.

Embodiments herein, for example, are described above with reference to block diagrams and/or operational illustrations of methods, systems, and computer program products according to said embodiments. The functions/acts noted in the blocks may occur out of the order as shown in any flowchart. For example, two blocks shown in succession may in fact be executed substantially concurrently or the blocks may sometimes be executed in the reverse order, depending upon the functionality/acts involved.

While certain embodiments have been described, other embodiments may exist. Furthermore, although embodiments herein have been described as being associated with data stored in memory and other storage mediums, data can also be stored on or read from other types of computer-readable media, such as secondary storage devices, like hard disks, floppy disks, or a CD-ROM, or other forms of RAM or ROM. Further, the disclosed methods' stages may be modified in any manner, including by reordering stages and/or inserting or deleting stages, without departing from the claimed subject matter.

Although the subject matter has been described in language specific to structural features and/or methodological acts, it is to be understood that the subject matter defined in the appended claims is not necessarily limited to the specific features or acts described above. Rather, the specific features and acts described above are disclosed as example forms of implementing the claims.

What is claimed is:

1. A vehicle-mounted garbage bin cleaning system, the system comprising:
  - a) a pair of arms configured for lifting a garbage bin, the pair of arms rotatably coupled to a mount on a vehicle;
  - b) a hopper configured for accepting the garbage bin when the pair of arms lifts the garbage bin into the hopper;
  - c) a first spray rod and a second spray rod, both extending upwards from the hopper and configured to wash an interior of the garbage bin, wherein each of the first and second spray rods include at least one high-pressure, rotating water nozzle that sprays a water jet;
  - d) wherein when the pair of arms lifts the garbage bin into the hopper, the first and second spray rods are situated within the garbage bin; and
  - e) a gas-powered motor coupled to the vehicle, the gas-powered motor dedicated to powering a first and a second pressure washer pump, wherein the motor drives a mechanical means comprising: 1) a first pulley connected to a first belt, and 2) a second pulley connected to a second belt;
  - f) the first pressure washer pump mechanically coupled to the first belt of the mechanical means via a pulley coupled to the first pressure washer pump such that the mechanical means drives the first pressure washer

14

pump, and the first spray rod being fluidically coupled with the first pressure washer pump such that the first pressure washer pump provides pressurized water to the first spray rod; and

5 g) the second pressure washer pump mechanically coupled to the second belt of the mechanical means via a pulley coupled to the second pressure washer pump such that the mechanical means drives the second pressure washer pump, the second spray rod being fluidically coupled with the second pressure washer pump such that the second pressure washer pump provides pressurized water to the second spray rod.

10 2. The vehicle-mounted garbage bin cleaning system of claim 1, wherein the mechanical means further comprises one or more shafts.

15 3. The vehicle-mounted garbage bin cleaning system of claim 2, wherein the mechanical means further comprises a first shaft coupled to the first pulley.

20 4. The vehicle-mounted garbage bin cleaning system of claim 3, wherein the mechanical means further comprises a second shaft coupled to the second pulley.

25 5. The vehicle-mounted garbage bin cleaning system of claim 1, wherein the hopper is configured to catch substantially all water that is sprayed by the first and second spray rods configured to wash the interior of the garbage bin.

6. The vehicle-mounted garbage bin cleaning system of claim 5, wherein the first spray rod includes a plurality of high-pressure, rotating water nozzles that spray water jets.

7. The vehicle-mounted garbage bin cleaning system of claim 6, wherein the second spray rod includes a plurality of high-pressure, rotating water nozzles that spray water jets.

8. The vehicle-mounted garbage bin cleaning system of claim 7, further comprising a water tank that provides a source of water to the first and second pressure washer pumps.

9. The vehicle-mounted garbage bin cleaning system of claim 8, further comprising:

a computing device programmed to automatically activate the pair of arms to lift the garbage bin into the hopper, and automatically activate the first and second pressure washer pumps to spray water and clean the garbage bin, and

a control panel for activating the computing device.

10. The vehicle-mounted garbage bin cleaning system of claim 8, further comprising:

a control panel for automatically activating the pair of arms to lift the garbage bin into the hopper, and for automatically activating the first and second pressure washer pumps to spray water and clean the garbage bin.

11. The vehicle-mounted garbage bin cleaning system of claim 10, wherein the control panel comprises a joystick for activating the pair of arms to grab and lift the garbage bin into the hopper.
